DESIGN FOR A MULTIPLE HOLDER FOR COSMETIC PREPARATIONS OR THE LIKE

Fred Frederics, New York, N. Y.

Application April 16, 1945, Serial No. 119,042

Term of patent 14 years

(Cl. D86—10)

To all whom it may concern:

Be it known that I, Fred Frederics, a citizen of the United States of America, residing in New York city, county of New York, and State of New York, have invented a new, original, and ornamental Design for a Multiple Holder for Cosmetic Preparations or the like, of which the following is a specification, reference being had to the accompanying drawing, forming part thereof, wherein,

The rear portion of the multiple holder for cosmetic preparations or the like, is substantially the same in appearance as the front.

I claim:

The ornamental design for a multiple holder for cosmetic preparations or the like, substantially as shown and described.

FRED FREDERICS.
